Patented May 28, 1968

211,161

SHOWER DOOR DRIP ASSEMBLY

Ralph T. Casebolt, 380 Elysian Field Drive,
Oakland, Calif. 94605

Filed June 22, 1967, Ser. No. 7,552

Term of patent 7 years

(Cl. D13—6)

FIG. 2

FIG. 5

FIG. 1

FIG. 3

FIG. 4

FIG. 1 is an end elevational view of the shower door drip assembly;

FIG. 2 is a top plan view of the shower door drip assembly;

FIG. 3 is a fragmentary side elevational view thereof;

FIG. 4 is a fragmentary bottom view; and

FIG. 5 is a perspective view thereof with the pane shown in broken lines for illustrative purposes only.

I claim:

The ornamental design for a shower door drip assembly, as shown and described.
